UNITED STATES PATENT OFFICE.

WILLIAM J. BRANIGAN, OF PHILADELPHIA, PENNSYLVANIA.

PORTABLE MOTION-PICTURE-PROJECTING MACHINE.

1,090,097.

Specification of Letters Patent. Patented Mar. 10, 1914.

Application filed March 31, 1913. Serial No. 758,028.

To all whom it may concern:

Be it known that I, WILLIAM J. BRANIGAN, a citizen of the United States, residing at Philadelphia, in the county of Philadelphia and State of Pennsylvania, have invented a new and useful Portable Motion-Picture-Projecting Machine, of which the following is a specification.

This invention relates to motion picture apparatus of that type utilizing an intermittently operating film strip.

Motion picture machines as heretofore constructed for the use of standard film strips have been of such size and weight as to require considerable care and expense in their transportation and the use of special facilities in order to utilize the machines. For this reason their field of use has been greatly limited.

One of the objects of the present invention is to so arrange and proportion the parts of the machine that the same can be stored compactly in a case and conveniently carried, it being possible to set up the machine quickly ready for use so that it can be used not only for ordinary public exhibition purposes but can be also set up in offices, residences, schools and the like for business, entertainment and educational purposes.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings:—Figure 1. is a side elevation of the machine, certain parts being broken away. Fig. 2 is a top plan view. Fig. 3 is a section on line A—B Fig. 1, the shutter being shown in elevation. Fig. 4 is a section on line C—D Fig. 2, showing the gear case with its face plate removed and the gear shafts in section.

Referring to the figures by characters of reference 1 designates a base which may be curved as shown and this base is provided with a laterally extending arm 2. The base

is provided, adjacent its ends with split sleeves 3 and the free end of arm 2 is likewise provided with a split sleeve 4. Each of these sleeves is adapted to receive the upper end portion of one leg 5 of a tripod and these legs can be of any construction desired. For example, each leg can be made of members telescopically connected so that they can be collapsed and stored in a small compass. Each split sleeve 3 and 4 is provided with suitable means whereby it can be clamped upon the upper end of the leg 5 therein. In the drawings, clamping screws 6 have been shown provided for this purpose.

Secured upon the base 1 is a gear case 7 having a removable face plate 8 upon the inner side thereof. A bracket 9 extends laterally from the face plate and carries a barrel 10 in which a lens tube 11 is adjustably mounted, the adjustment of this tube being effected in any manner desired. Directly back of the lens tube is a laterally extending plate 12 likewise extending from the face plate 8 and formed with an angular orifice 13 the center of which is in alignment with the longitudinal axis of the lens tube 11.

Arranged directly back of the plate 12 is a guide plate 14 connected at its upper and lower ends to the plate 12 by means of posts 15 or the like. This guide plate 14 has side ribs 16 between which the film strip is adapted to move. An opening or light passage 17 is formed in the guide plate 14 and is preferably of the same size as the opening 13, the center of this opening or light passage 17 being in alignment with the longitudinal axis of the lens tube 11.

Hingedly connected to the face plate 8 is a back plate 18 having a light passage or opening 19 the center of which is in alignment with the longitudinal axis of the lens tube 11. This hinged plate may be secured in active position in any preferred manner, as by means of a pivoted latch 20 mounted on a post 21 and adapted to enter a slot 22 formed in the hinged plate 18 so as thus to bind the plate against the post 21. A clamping frame 23 is provided with pins 24 slidably mounted in the hinged plate 18, there being springs 25 mounted on these pins and bearing against the hinged plate 18 and the frame 23 so as thus to hold the frame normally pressed into the space between the guide ribs 16 so as to clamp a film strip

against the guide plate 14. The opening in the clamping frame 23 is similar to the openings in the plates 12 and 14.

A post 26 extends rearwardly from the 5 arm 2 and is designed to support a lamp. This lamp, which is shown at 27, is preferably mounted on a standard 28 which is detachably and adjustably secured to the post 26 so that the front end of the lamp can 10 thus be removably held directly back of the aperture in the plate 18, as shown in Figs. 1 and 2.

The plate 12 has a depending arm 29 in which is journaled one end of a shaft 30 15 which extends into the casing 7 and is provided with a star wheel 31 such as commonly employed in machines of this character. Secured to this shaft 30 directly below the plate 12 is a sprocket drum 32 and a 20 post 33 is located below the sprocket drum 32 and has arms 34 mounted to swing thereon, these arms carrying an idler roll 35 designed to hold a film strip in engagement 25 with the sprocket drum 32. A spring 36 is mounted on the post 33 and serves to press the roll 35 yielding against the film strip when interposed between the roll 35 and the sprocket drum 32.

An operating shaft 37 is journaled in the 30 case 7 and its face plate 8 and also in a tubular post 38 provided therefor and this shaft may be rotated in any suitable manner, as by means of a crank 39. Secured to shaft 37 within case 7 is a drive gear 40 35 which meshes with a smaller gear 41. A larger gear 42 meshes with another large gear 43 secured to the shaft 44 of the upper sprocket drum 45 of the apparatus, this sprocket drum being located in front of the 40 upper portion of plate 12 and being adapted to engage the film strip so as to feed it to the guide plate 14 and the holding frame 23. An idler roll 46 is arranged to press the film strip into engagement with the sprocket 45 drum 45 and can be mounted in the same manner as the roll 35 hereinbefore described. Gear 40 also meshes with a small gear 47 secured to the shaft 48 of a sprocket drum 49, this sprocket drum being located under the 50 lens tube 11 and being adapted to engage the film strip and feed it toward a takeup reel at a predetermined speed. This sprocket drum 49 has an idler roll 50 located adjacent thereto for the purpose of holding the film strip 55 into engagement with the sprocket drum. This idler roll can be mounted in the same manner as the rolls 35 and 47 hereinbefore referred to. Gear 42 meshes with a small gear 51 secured to a shaft 52 which extends laterally from the gear case 7 and is journaled at its outer end in an arm 53 extending downwardly from plate 12. A disk 54 is secured to shaft 52 within case 7 and carries a pin 55 for actuating the star wheel 31. 60 A retaining disk 56 also rotates with shaft

52 and serves to hold the star wheel against rotation except when pin 55 is in engagement with said star wheel. This construction is the same as that commonly employed in other machines of this class and does not 70 constitute any part of the present invention.

A bevel gear 57 is secured to shaft 52 and meshes with a bevel gear 58 mounted for rotation on a stud 59 which extends forwardly and upwardly from arm 53 and through the 75 center of a frusto-conical shutter 59. This shutter is so shaped that a vertical plane passing through the center of the shutter and through the centers of the openings 13 and 17 will intersect the shutter along a straight line parallel with the plate 12, as 80 will be apparent by referring to Fig. 1. The lower portion of the shutter extends under the lower end portion of the lens tube 11 and thus it will be seen that the parts of the 85 mechanism can be compactly arranged without interference with the operation of the shutter.

An arm 68 extends upwardly from the gear case 7 and carries a laterally extending 90 spindle 69 on which the reel 70 is adapted to rotate. Another arm 70' extends downwardly and forwardly from the gear case and carries a shaft 71 to which a takeup reel 72 is adapted to be keyed in any suitable manner. This shaft has a pulley 73 95 adapted to receive motion, through a belt 74, from a pulley 75 secured to and rotating with the shaft 44. Pulley 73 is not keyed on shaft 71 but is held thereon by friction 100 so that by gearing up the parts to cause reel 72 to pull on a film strip faster than the strip can be withdrawn from the sprocket drum 49, the pulley 73 will slip on shaft 71 and thus cause a constant drag upon the 105 shaft with the result that the reel 72, which is being held back by the film strip, will cause the film strip to wind tightly upon the reel.

In the drawings, the film strip has been 110 shown at F and extends from the reel 70 downwardly under the sprocket drum 45 and is looped over the idler roll 46 so as thus to feed downwardly between the guide plate 14 and the clamping frame 23. The 115 film strip passes between the sprocket drum 63 and the idler roll 35, thence over roll 50 and under sprocket drum 49 to the takeup reel 72, a guide roller 76 being preferably located below the sprocket drum 49 so as to 120 properly guide the film strip to the takeup reel 72.

It will be apparent that when the drive shaft 37 is rotated, motion will be transmitted therefrom through the several gears 125 to the different sprocket drums and the star wheel 31 will be operated intermittently by the pin 55 so as thus to produce an intermittent movement of the sprocket drum 32 and, consequently, an intermittent feed of 130

the film strip across the field of light projected from the lamp to the lens tube. During the rotation of the various sprocket drums, motion will be transmitted through 5 shaft 52 and gears 57 and 58 to the frustocylindrical shutter 59.

If desired a stirrup 77 can be suspended from the arm 2 by means of a chain 78 or the like and by placing a foot in this stirrup 10 and pressing downwardly, the operator of the machine can hold the same steadily while crank 39 is being rotated.

Importance is attached to the fact that the device herein described is so constructed 15 that the various parts thereof can be detached and the machine thus compactly stored within a case so that it can be conveniently carried. Furthermore the machine can be quickly set up and by employing 20 an incandescent lamp having a suitable reflector, the apparatus can be successfully operated in small rooms or wherever it is not necessary to project pictures over ten or twelve feet. By using arc lights, however, 25 the machine can be used for projecting pictures considerable distances and will be found as efficient for entertainment purposes as the ordinary larger and heavier machines commonly employed at this time.

30 In order to facilitate the operation of the

machine, a fly wheel 79 may be secured to one of the shafts as, for example, shaft 52.

Any suitable framing mechanism, indicated generally at 63, may be used in connection with the machine.

35

What is claimed is:—

1. A knock-down portable motion picture projecting machine including a base, a gear case on the base, film supporting and actuating means extending from said case, supporting legs detachably connected to the base, and a lamp detachably connected to the base. 40

2. A motion picture projecting machine including a casing, upper and lower reels, a film guide extending laterally from and located entirely outside of the casing, film sprockets extending laterally from and located entirely outside of the casing, means within the casing for actuating the sprockets, a bracket extending laterally from and located entirely outside of the casing, and a lens tube carried by the bracket. 45

In testimony that I claim the foregoing as my own, I have hereto affixed my signature in the presence of two witnesses.

50 WILLIAM J. BRANIGAN.
